UNITED STATES PATENT OFFICE.

HENRY M. PIERCE, OF NASHVILLE, TENNESSEE.

FURNACE FOR THE MANUFACTURE OF COKE.

SPECIFICATION forming part of Letters Patent No. 330,732, dated November 17, 1885.

Application filed April 1, 1885. Serial No. 160,933. (No model.)

To all whom it may concern:

Be it known that I, HENRY M. PIERCE, a citizen of the United States, residing at Nashville, in the county of Davidson and State of Tennessee, have invented certain new and useful Improvements in Furnaces for the Manufacture of Coke; and I hereby declare the following to be a full, clear, and exact description of the same, reference being had to the accompanying drawings, which form a part of this specification.

The method commonly practiced in this country for the manufacture of coke consists in the use of small mound-shaped ovens about ten feet in diameter at the base, and adapted to hold a charge of about four tons, or one hundred bushels. The firing is done at the top, and the coking process proceeds from above downward, first supported by combustion of the upper layer of coal and afterward by the volatile matter and gases evolved from the deeper layers, and which becomes ignited and burns in the upper or vacant portion of the oven. The air to support combustion is admitted in limited quantities by means of ports or around the top of the coke-oven door. The difficulties encountered by this method are, first, loss from the per cent. of coal consumed in the early stages of the process; secondly, loss from the imperfectly-cooked mass, which remains in the oven; thirdly, the loss from or waste of the large percentage of the heating-power of the volatile matter, gases, &c., which burn in the upper part of the oven, and as a result thereof, and, fourthly, the unequal heating of the oven and the unnecessarily slow progress of the coking.

To avoid the cost entailed by the use of small ovens, and in a measure the loss from the imperfectly-cooked mass remaining in the bottom of the oven, large kilns open at the top, have been employed, and the coking process conducted by cross-firing and by proceeding from below upward, for which purpose a series of horizontal air and draft flues were constructed in the bottom of the charge; but by this method, though the limitation of the charge was avoided, the loss from consumed coal still resulted, and the loss of the heating value of the gas and volatile products was augmented.

A third mode of procedure has been to employ a series of vertical retorts surrounded by combustion-flues, wherein the gas evolved from the coking-charge was burned to heat the retort and perform the coking. By this means, while the heating value of the evolved gas, &c., was saved, the capacity of the oven and plant was limited, with all its attendant cost and disadvantages, save the unequal heating of the charge.

Having above pointed out the methods commonly practiced and the means employed, I will now first indicate generally the character of my invention, and then describe specifically the best manner known to me of carrying it into effect. Its objects are to avoid loss of fuel by direct combustion of any portion of the charge, therefore I conduct the process by radiated heat; secondly, to utilize all the heating value of the evolved gases, consequently I utilize said gases as the fuel for producing the heat to heat the whole charge uniformly, and at the same time to avoid the deposit of tarry matter and the production of an imperfectly-cooked mass at the bottom of the charge and attendant loss, so I apply the radiated heat at the bottom of the charge; and, finally, to avoid limiting the size of the charge to be treated, and this results as a sequence of applying the heat at the bottom of the charge.

I will now proceed to describe specifically the apparatus which I have devised for this purpose.

In the drawings, Figure 1 is a perspective view of a battery of several coke-ovens, constituting a plant or works. Fig. 2 is a vertical longitudinal section of an oven and its appurtenances. Fig. 3 is a horizontal section on the line *x x*, Fig. 2, showing the charge or coking chamber. Fig. 4 is a similar section on the line *y y*, Fig. 2, showing the main combustion-chamber and radiating or branch combustion-chamber.

Like letters refer to like parts wherever they occur.

A A A indicate a series of ovens of like character arranged in battery. Each oven is by preference of a rectangular or quadrilateral form, having its outer walls of brick or stone, with a lining of fire-brick, if preferred, and, if

found necessary, a packing or dead-air space between the outer wall and lining, as in constructing same classes of blast-furnaces. In size it generally exceeds an ordinary coke-oven, having a capacity of, say, from forty to sixty tons, being practically limited only by the convenience of the manufacture. At the bottom, and extending longitudinally, (and preferably centrally from end to end,) is an arched flue, tunnel, or combustion-chamber, B, from which at short intervals extend transverse branches b, which terminate in lateral collecting-flues C, leading to suitable chimneys, c. The number and arrangement of the branches b will be such as to form, practically, a hollow hearth or bottom for the whole oven. The chimney c may be of triangular form and occupy the corners of the oven, thus saving space and giving to the oven an interior form, which facilitates the withdrawal of the coke.

Directly over the combustion-chamber B and its branches b is laid the floor of the coking-chamber. At each end of the oven A are two or more doors, a a, through which the oven may be charged and the coke withdrawn when the coking process is finished, and separating the doors or occupying the spaces between the same at each end of the oven is situated a chamber, also of triangular cross-section, and forming a dead-air space extending from the floor to the roof of the coking-chamber.

It will be observed that the triangular form of the chimneys c and chamber c' economizes space, and at the same time frees the oven of corners or pockets, which might not be readily accessible when removing the coke. Each chimney may be provided with a steam-jet to induce a draft therethrough when desired.

In the crown or arch of the oven are two or more gas-ports, a', which may be also used as charging-ports for introducing coal when desired. These ports are provided with stoppers for closing the same when not in use.

In the end walls of the oven, just below the crown or arch, (one or more at each end,) are gas-pipes d, provided with valves d', and delivering into a receiving-main, D. In this pipe d, just beyond the valve d', is arranged a steam-jet, e, which may be supplied with steam from any suitable source; and extending from the receiving-main D at a point opposite the pipe d is a valved cross-pipe, d'', which connects with a delivery-main, E, from which a branch gas-pipe, d'', provided with a steam-jet, projects into the combustion-chamber B. The function of the steam-jets in the pipes d and d'' is respectively to act as ejectors or injectors of the combustible gases. This construction is preferably applied to each end of the furnace, as shown in Fig. 2, so that the heat may be uniformly distributed throughout the passageways b.

When a single oven A is employed, the receiving-main D and delivering-main E E may be dispensed with, and the pipes d d'' d''

may be consolidated and have but a single steam jet and valve.

The above description, which has been limited to a single oven, is to be understood as applying to each oven of the series shown.

I will next describe the arrangement and connection of ovens when a series or plant is employed.

Any number of ovens A, according to the size of the ovens and the capacity of the desired works, are arranged in line in juxtaposition, and the gas exits or pipes d of each oven are connected with receiving-mains D, which extend the length of the battery. There are also delivery-mains E (one for each side of the battery, as is the case of the receiving-main D) extending the length of the battery parallel with and below the receiving-mains, and these mains are connected with the gas-pipes d''. Where the volatile vapors and gases evolved from the coking coal are to be used in the condition in which they come from the ovens, the receiving-main D may be connected directly with the delivery-mains E by the by-paths F alone; or, as it is sometimes desirable to eliminate from the gases evolved in the oven the ammonia, &c., a condenser or scrubber, G, may be interposed between the receiving-main D and the delivery-main E, so that the gas, &c., can be used in natural condition or after treatment, as preferred.

The devices being substantially of the character hereinbefore specified, the process will be conducted therein as follows: The ovens are duly charged with the coal to be coked, and where the plant is first originally put in operation the charge is heated by radiated heat from a fire kindled in the combustion-chamber B, the gas-ports a' are opened, and the fire being urged, the vapors, gases, &c., are permitted to escape at a' until they are found to be of an inflammable character. When this occurs, the valves d' of pipes d are opened and the ports a' closed, which permits the evolved gases, &c., to enter the receiving-main D. Jets e may then be started (the valve in cross-pipe d'' being opened) and the gas forced directly from the oven through the pipes d d'' d'' into the combustion-chamber B, (at each end of the oven,) where, being ignited, it burns, developing an intense heat, which is distributed through the various branch flues b into the hollow coking-chamber, and radiates into the base thereof, the gases evolved from the charge serving to convey the heat into upper layers thereof, so that the coking process progresses upward from below rapidly and uniformly until the whole charge is coked. Toward the close of the coking process, if it is desired to expedite matters and insure the perfect coking of the upper layer, the steam-jet e and damper d' in the pipe d may be closed, so as to cut off the oven from the receiving-main D. The ports a' may be then opened, and the gas remaining in the top or upper part of the kiln may be ignited

therein, so as to apply a more direct and immediate heat to the upper layer of the charge. This is an advantage, but not an essential. Where the ovens are worked in batteries, as shown in Fig. 1, the valves of the cross-pipes d^2 may be closed, and the gas, after entering the receiving-main D, may pass the length thereof and into delivery-main E, either directly by the by-paths F, or after passing through the condensers, scrubbers, &c., at G.

As each chimney c is provided with a steam-jet and a damper, (which are not shown, as they can be of any common and well-known character,) in case the coking should be progressing more rapidly at one part of the coking-chamber than at the other, the jets can be temporarily turned off and the chimneys closed on that set or portion, and the whole or larger part of the heating-flame turned under that portion of the coking-chamber where the process is progressing more slowly, and thus the balance or equilibrium can be restored. This advantage is one of the incidents of heating by radiation through base-flues of the general character specified.

As the various pipes and mains d, d^2 , d^3 , D, and E are provided with suitable valves, steam-jets, and connections, as hereinbefore specified, it is apparent that any one or more of the ovens can be cut out of the series when it is to be charged or the coking withdrawn; that when the battery has once been put in operation that operation can be continuously maintained without other fuel than the gas evolved from the coal in the coking process, and that any oven may be heated either by the gas evolved therein or by gas from any oven of the battery, and consequently the ovens, though arranged in batteries, may be operated independently.

I do not herein claim the method or process set forth in the specification, as the same forms the subject-matter of application No. 139,263, filed July 31, 1884; but I restrict the invention to the apparatus described.

I am aware that it has been proposed to provide an elliptical coke-furnace with pairs of chimneys communicating with a combustion-chamber and its flues, and located at opposite ends of the furnace-bed and outside of

the walls thereof. Over such construction the invention described in my claims has obvious advantages of simplicity of structure and economy of production.

I am also aware that, with the exception of the valved cross-pipes connecting the receiving and delivery mains, the combination set forth in my third claim is not new. From what has gone before, however, it will be apparent that the presence of such cross-pipes largely increases the control of the operator over the work carried on throughout the battery, multiplying the number of possible manipulations.

Having thus described my invention, what I claim, and desire to secure by Letters Patent, is—

1. A rectangular coking-oven having a coking-chamber, a combustion-chamber, and a series of flues arranged below the floor, and 70 chimneys arranged in the corners of the coking-chamber within the oven-walls, and communicating with the combustion-chamber, substantially as and for the purposes specified.

2. A rectangular coking-oven having a coking-chamber, a series of combustion-chambers, B b, arranged below the floor thereof, and a series of chimneys, c, and chambers c', triangular in cross-section, and arranged within the coking-chamber, substantially as and for 80 the purposes specified.

3. A battery of coke-ovens having each a closed coking-chamber and basal combustion-chamber, in combination with a receiving-main extending along and common to all the 85 ovens, valved branch pipes joining said main with each of the closed chambers, a delivery-main parallel to the receiving main, valved cross-pipes connecting the two mains, and valved branch pipes connecting the delivery- 90 main with each of the combustion-chambers, substantially as and for the purposes specified.

In testimony whereof I affix my signature, in presence of two witnesses, this 11th day of March, 1885.

HENRY M. PIERCE.
